WINDOWED COOKING STOVE

Elmer D. Pellegrin, Woodstock, Ill., assignor to
 A. J. Lindemann & Hoverson Company, Milwaukee, Wis., a corporation of Wisconsin

Application August 19, 1944, Serial No. 550,291

9 Claims. (Cl. 126—200)

1

The improvements relate to cooking ranges provided with ovens, and among their objects are the provision of means mounted in the range whereby the interior of the oven and food therein may be made visible and clearly and easily observed by a person standing in normal posture; to so construct such means that they will be protected against heat, smoke and other products of combustion and cooking and against accidental injury; to so construct and arrange them that they will not only give the operator a direct downward view of the oven from front to back but will illuminate its interior by light coming from above it and projected upon the top of the food cooking therein instead of indirectly as through an oven door window or peep glass.

Other objects and advantages will be apparent to those familiar with the construction and uses of ovens from the following description of an exemplary embodiment of the invention.

The improvements are illustrated in the accompanying drawings, referred to herein, in which—

Fig. 1 is a front view of a gas range with oven embodying the improvements;

Fig. 2 is a vertical section substantially on the line 2—2 of Fig. 1, looking in the direction of the arrows.

Heretofore it has been the practice of some manufacturers to provide transparent panels in the oven doors of their ranges, and such panels usually consist of a sheet of relatively heavy plate glass. These are open to the objections that the glass panels being in close proximity to the cooking zone, even when made double, radiate heat, become very hot, add to the weight of the door and sometimes become broken, do not sufficiently illuminate the oven because the light admitted therethrough is indirect, and are sometimes brought in contact with cooking pots and pans and their contents when such vessels are being placed in or removed from the oven. But perhaps the chief objection is that it is necessary for the operator to kneel down or stoop over and approach close to the oven door in order to look through the glass. There are other unsatisfactory features, including the fact that the light admitted by these transparent panels does not come from above the oven directly, and is therefore in most cases quite insufficient to give a clear view of the food being cooked. To remedy this last fault, artificial illumination, such as that of incandescent electric light bulbs has been used, and also reflectors intended to reflect light from the sky or from

2

the illumination of the room have been used. These, however, are only a partial remedy, and the well recognized need for a device which will give a direct view of the oven and its contents and avoid opening the oven door for that purpose has not been heretofore met by any satisfactory device.

The present improvements may be used in combination with artificial illumination of the oven where the light above and around the oven is not good, but in a good light can be used without such interior illumination, and will serve far better than the ordinary transparent door window. If desired, they may be employed in combination with the door window and with or without the interior illumination. But whether used alone or in combination with such other illuminating means, the results are far superior and relieve the operator of considerable trouble and inconvenience, giving a full view of the oven and its contents from a standing position. The form and recessed mounting of the present window also protect it against accidental injury, and the fact that it is spaced a considerable distance from the oven and provided with a protecting glass panel between it and the oven compartment, which can be quickly and easily cleaned, prevents it from becoming fouled and obscured by smoke and other combustion and cooking products and provides excellent insulation against heat radiation.

The improvements are primarily designed to be used in the ovens of gas ranges, but may be employed in electric ranges and even, with suitable adaptations, in ranges heated by solid or liquid fuel.

In the drawings, 1 represents the exterior of a gas range having a top 2, sides 3, oven compartment 4 and oven door 5, which in this case is of the sliding type and provided with a handle 6 for opening and closing it.

In the top wall 7 of the oven there is provided an opening with an upwardly flared edge 11, and upwardly from this opening to the front of the range between the top of the door and the oven top extends a tubular member 8. At the outer end of this tube and in the open front frame member 10 is mounted an inwardly curved glass window panel 9 the face of which is partly at least approximately normal to the length of the tube, so that a person can look down therethrough and view the interior of the oven from above. The tube 8 is secured at its lower end to the flange 11 of the top wall 7, and between the upper edge of this flange and a circumferential

interior bead 12 of the tube a transparent plate 13 covering the oven opening is secured. The upper edges of the tube are secured in the turned over edges of the opening of frame member 10 at 14 and curved transparent window panel 9 closes this opening. It will thus be seen that the interior of the tube and the window 9 are protected against smoke, steam, grease and other combustion and cooking products and insulated against heat.

The cross section of the tube 8 and the plate 13 correspond to the size and outline of the window 9 and offer no material obstruction to the view of the oven interior afforded by the latter and the plate when it becomes obscured can be easily cleaned by a cloth applied to its under surface. The position of the backwardly curved window 9 near the top of the range and its backward inclination bring it approximately in the line or field of vision of a person standing in front of the oven and therefore enable the operator to view the interior of the oven and its contents without stooping and from a safe distance. This window can also be used when the oven door is opened and the cooking food is turned, basted or otherwise attended to, without requiring the face of the operator to be brought into proximity to the oven opening. The light passing into the oven through the window 9 is direct light from the sky or from the ceiling illumination of the room and strikes downwardly into the oven and substantially parallel with the line of vision of the operator, and it is well known that light of this character projected in this manner renders objects more visible, as evidenced by universal practice of experienced photographers of securing such a light whenever possible.

The position of the window 9 substantially inside the front frame of the stove tends to protect it against accidental breakage and from becoming obscured with dirt, grease or other foreign matter. Its curved form not only improves vision through it but makes it stronger and breaks up light reflections, like the crystal of a watch. However, if the window were made plane it would serve its purpose very well, and much better than all other oven windows now in use.

An oven door window 15 is indicated in Fig. 1, and such a window may be employed if desired to augment the light admitted by the window 9 and obviate the necessity for artificial illumination of the oven in relatively dark places. Illumination may also be provided by the horizontal tubular electric light bulb 16 plugged into the side of the oven at 17 and operated by a suitable snap or button switch to impart current to it from the house lamp circuit or flashlight storage batteries. This lamp extends laterally across the top of the oven at the rear part thereof and is enclosed by a reflector 18 and a glass window 19 set in the top wall of the oven at 20. As illumination of this character is used in ovens and other compartments requiring it and is found in prior patents, the details need not be further described. It should, however, be arranged substantially as shown or in some other manner which will not permit it to interfere with the light entering the oven through the window 9 or the view of the operator therethrough, and it will not be found necessary in most cases where adequate sky light or ceiling illumination is present.

If the oven is located under top burners of a gas range the outer sight window and its passage can be located between the valve rods and their exterior handles, the rods in that case diverging

frontwardly and the handles being spaced apart to make room for them.

The opening 21 at the front of the oven is closed by the door 5 which forms when so closed a part of the enclosing frame of the range, which in the illustrative embodiment shown is of the console type, and its inner vertical wall 5' is then within the outer edges of the top 7 and side walls 22 of the inner oven shell so as to provide a tight closure. The opening 23 in the top wall of the oven is within this inner face of the door so as to be unobstructed thereby, but the opening and the sight glass 9 may be combined with a special construction of the door so as to be carried thereby and at the same time give a top downward view of the oven interior and catch vertical rays of light from above the oven.

Various other changes in details of construction may be made without departing from the scope of the invention.

What I claim is:

1. In a cooking range, an outer enclosing frame or housing comprising front and top portions, an oven compartment therein comprising a top and sides, one of the sides having a front opening, a door for said opening having its top below the top of the frame and forming in effect when closed a portion of said frame front portion, said front portion having an obliquely arranged sight opening at its upper part inclined inwardly and at least partly exposed to light rays coming from above the range, a transparent cover for said sight opening, said oven having an opening in visual alignment with said sight opening, said range having a visually unobstructed space between and through the two last mentioned openings and open to the interior of the oven and in fields of vision projected from the space above and laterally removed from the range.

2. In a cooking range, an outer enclosing frame or housing comprising front and top portions, an oven compartment therein comprising a top and sides, one of the sides having a front opening, a door for said opening having its top below the top of the frame, a window in said door for admitting light to the interior of the oven, said front portion having a sight opening in an obliquely arranged portion at its upper part at least partly exposed to vertical light rays coming from above the range, a sheet of transparent material closing said sight opening and conforming thereto in position, said oven top having an opening in visual alignment with said sight opening, said range having a visually unobstructed space between and through the two last mentioned openings and open to the interior of the oven and in fields of vision projected from the space above and removed from the range.

3. In a cooking range, an outer enclosing frame or housing comprising front and top portions, an oven compartment therein comprising a top and sides, one of the sides having a front opening, a door for said opening, an obliquely arranged window at the upper part of said front portion inclined inwardly and at least partly exposed to vertical light rays coming from above the range, said oven having a top opening in visual alignment with said front window, said range having a visually unobstructed space between and through the said window and oven top opening and open to the interior of the oven and in fields of vision projected from space above and removed from the range, and an illuminating device in the upper part of said oven to the rear of said top opening.

4. In a cooking range, an outer enclosing frame or housing comprising front and top portions, an oven compartment therein comprising a top and sides, one of the sides having a front opening, a door for said opening, an obliquely arranged window at the upper part of said front portion inclined inwardly and at least partly exposed to light rays coming from above the range, said oven having a top opening in visual alignment with said front window and spaced inwardly and downwardly therefrom, said range having a visually unobstructed sight space between and through the window and said oven top opening and open to the interior of the oven and in fields of vision projected from space above and removed from the range.

5. In a cooking range, an outer enclosing frame or housing comprising front, side and top portions, an oven compartment therein comprising a top and sides, one of the sides having a front opening, a door for said opening, said frame having a sight opening at its upper part which is inclined inwardly and at least partly exposed to light rays coming from above the range, said oven top having an opening in visual alignment with said sight opening, said range having a visually unobstructed space between the two last mentioned openings and visually open to the interior of the oven and to space above and removed from the range, a transparent cover for said sight opening, said inclined sight opening being at least partly within the outer surfaces of the outer enclosing frame.

6. In a cooking range, an outer enclosing frame or housing comprising front, side and top portions, an oven compartment therein comprising a top and sides, one of the sides having a front opening, a door for said opening, said frame having a sight opening at its upper part which is exposed to light rays coming from above the range, said oven top having an opening in visual alignment with said sight opening, said range having a visually unobstructed space between the two last mentioned openings and visually open to the interior of the oven and to space above and removed from the range, a transparent cover for said sight opening, said sight opening being at least partly within the outer surface of the outer enclosing frame.

7. In a cooking range, an outer enclosing frame or housing comprising front, side and top portions, an oven compartment therein comprising a top and sides, one of the sides having a front opening, a door for said opening, said frame having a sight opening above said door which opening is inclined inwardly and at least partly exposed to light rays coming from above the range, a sheet of transparent material in said sight opening inclined therewith and upwardly convex, said oven top having a horizontal opening in visual alignment with said frame sight opening, a transparent closure therein, said range having a visually unobstructed space between the two last mentioned openings and visually open to the in-

terior of the oven and to space above and removed from the range, said inclined sight opening being positioned at least partly within the outer surfaces of the outer enclosing frame and said transparent sheet therein having its upper part beneath the top portion of the frame.

8. In a cooking range, an outer enclosing frame or housing comprising front, side and top portions, an oven compartment therein comprising a top and sides, one of the sides having a front opening, a door for said opening, said frame having a sight opening at its upper part which opening is exposed to light rays coming from above the range, said oven top having a substantially horizontal opening at its front in visual alignment with said sight opening, said range having a visually unobstructed space between the two last mentioned openings and visually open to the interior of the oven and to space above the range, a transparent cover for said sight opening, an artificial illuminating device in said oven back of said oven top opening, and means for intercepting rays of light from said device located between it and said last named opening.

9. In a cooking range, an outer enclosing frame or housing comprising front, side and top portions, an oven compartment therein comprising a top and sides, one of the sides having a front opening, a door for said opening, said frame having a sight opening at its upper part which opening is exposed to light rays coming from above the range, said oven top having a substantially horizontal opening at its front in visual alignment with said sight opening, a transparent closure therein elevated above said oven top, said range having a visually unobstructed space between the two last mentioned openings and visually open to the interior of the oven and to space above the range, a transparent cover for said sight opening, a laterally extending artificial illuminating device in said oven back of said oven top opening, and means for intercepting rays of light from said device located between it and said last named opening.
